GAS-CARBURETTING APPARATUS

Reynold A. Peduzzi, Trafford, Pa.

Application April 24, 1951, Serial No. 222,633

14 Claims. (Cl. 48—184)

My invention relates to gas-carburetting apparatus for supplying a mixture of air and propane, natural gas, or other fuel-gas to the suction-intake of an internal-combustion engine or other combustion-device.

My present invention is an improvement over the gas-carburetor of my Patent 2,209,206, granted July 23, 1940, including such improved features as: a gas-pressure regulator which is capable of receiving compressed gas at pressures up to 150 pounds per square inch and delivering said gas, in as large quantities as may be required, at outlet pressures of less than a pressure of 4 ounces per square inch over the prevailing atmospheric pressure; a gas-metering carburetor-valve, cooperating with a similar gas-metering valve in the regulator, for admitting progressively increasing rates of gas-flow, depending sensitively upon the amount of valve-opening; an opening-spring for balancing, or partially counteracting, my previously used closing-spring, and operating on the carburetor-valve with an opening-force when the carburetor-valve is closed, the valve-opening spring-force becoming smaller when the carburetor-valve begins to open; and an auxiliary starting-and-idling diaphragm, which co-operates with my previously used main carburetor-diaphragm by assisting in opening the carburetor-valve during starting and idling, and which provides a steady, preadjustable, idling-speed of the engine.

With the foregoing and other objects in view, my present invention consists in the combinations, systems, parts, and methods of design and operation, as hereinafter described and claimed, and illustrated in the accompanying drawing, wherein

Figure 1 is a simplified and somewhat idealized diagrammatic vertical sectional view of an illustrative form of regulator-and-carburetor assembly embodying my invention, the section-plane through the carburetor being indicated approximately at I—I in Fig. 2, and

Fig. 2 is a larger-scale horizontal sectional view of the carburetor, on the section-plane indicated approximately at II—II in Fig. 1.

As shown in Fig. 1, my gas-carburetting apparatus comprises a gas-pressure regulator 3, and a gas-carburetor 4, the latter delivering a gas-and-air mixture to the butterfly throttle-valve 5 which is adapted to be connected to the suction-inlet of an engine (not shown).

The regulator 3 consists of a closed housing 6, having a high-pressure gas-inlet 7, a low-pressure gas-outlet 8, and a gas-metering regulator-valve 9. The valve 9 is movable from a position closing the high-pressure gas-inlet 7, to various amounts of valve-openings. It has a long tapered conical shape, so that it admits progressively increasing rates of gas-flow, depending sensitively upon the amount of opening-movement of the valve.

For automatically and simply controlling the regulator-valve 9, I provide a diaphragm 11, or other flexibly mounted regulator-controlling pressure-plate, which separates the interior of the regulator from the external atmosphere. Usually, the diaphragm is protected externally by a dished cap or cover-plate 12, which is provided with a vent 13 for restrictedly venting the space within the cover-plate 12 to the external atmosphere. The in-and-out movements of the diaphragm 11, in response to pressure-variations, are communicated to the regulator-valve 9 by a second-class lever 14, or other regulator-operating mechanical-connection means, preferably some form of motion-reducing mechanism resulting in greater forces on the valve 9 than the forces developed by the diaphragm 11. The effective pressure-area of the diaphragm 11 is suf-

2

ficiently large so that the valve 9 is closed when the internal pressure within the regulator is approximately that of the surrounding atmosphere. Preferably, the regulator-valve 9 begins to open when the internal regulator-pressure falls below a critical pressure which is 4 ounces per square inch over the prevailing atmospheric pressure, or other slight amount in excess of the external atmospheric pressure.

The carburetor 4, as shown in Fig. 1, comprises a venturi 15 having an air-inlet end 16 and a mixture-outlet end 17. Alongside of the venturi 15 is a gas-supply chamber 20 which is provided by a dished plate 21 and a main carburetor-opening diaphragm 22, or other flexibly mounted pressure-plate which separates the interior of the gas-supply chamber 20 from the external atmosphere. This diaphragm 22 is protected externally by a dished cap or cover-plate 23, which is disposed over the external side of said diaphragm 22, so that the space within the cover-plate 23 constitutes an external chamber 24 for the diaphragm. This cover-plate 23 is provided with a vent 25 for restrictedly venting said external chamber 24 to the external atmosphere. The gas-supply chamber 20 is provided with a gas-supply connection 26 to a suction-point in the venturi 15, and preferably this connection to the venturi is made at the point of maximum suction, which is just beyond the throat 27 of the venturi, or just after the inflowing air passes the point 27 of minimum cross-section in the venturi.

Disposed at the center of the dished plate 21 of the gas-supply chamber 20, as shown in Fig. 2, is a gas-inlet chamber 30, which is provided by means of a bore 30 in a casting 31, said bore being at right angles to the main carburetor-closing diaphragm 22. At one end, the gas-inlet bore 30 is provided with a gas-outlet 32 to the gas-supply chamber 20. Disposed within this gas-inlet bore 30 is a gas-metering carburetor-valve 33 which co-operates with the gas-outlet 32. This valve 33 has a valve-stem 34 which extends into the gas-supply chamber 20, where it is fastened to the center of the main carburetor-opening diaphragm 22 as shown at 35. The other end of the gas-inlet bore 30 is shown as being provided with a short threaded tubular extension 36, which is closed, in turn, by a removable cap 37. Disposed within the gas-inlet bore 30, back of the carburetor-valve 33, is a closing-spring 38, which is compressed by an adjustable nut 39 within the threaded tubular extension 36, preferably having self-locking threads. Threaded through this nut 39 is a maximum-opening abutment-rod 40 which provides an adjustable maximum-opening distance 41 through which the carburetor-valve may be opened by the main diaphragm 22, as will be subsequently described.

As shown in Fig. 2, the casting 31, which has the gas-inlet chamber or bore 30 therein, is provided with a lateral communicating-opening 43 which serves as a gas-inlet, being connected to the regulator-outlet 8 (Fig. 1) by means of a low-pressure gas-pipe 44.

In accordance with my present invention, as shown in Fig. 2, I also provide the outer cover-plate 23 of the main carburetor-opening diaphragm 22 with a centrally disposed, outwardly projecting, pipe-extension 45, within which is disposed a carburetor-valve opening-spring 46 which is compressed between the outer face of the main diaphragm 22 and an adjusting nut 47 which is threaded within the pipe-extension 45. The opening-spring 46 is centered on an outward valve-stem extension 34', which constitutes, in effect, a continuation of the valve-stem 34. The valve-stem extension 34' extends all the way through a guide-hole 48 in the adjusting nut 47, so that it has a sliding motion within said hole 48 as the main diaphragm 22 moves in and out, in response to pressure-changes.

In accordance with my present invention, as further shown in Fig. 2, I provide the outer end of the pipe-extension 45 with a short threaded tubular extension 49 which is secured to, and opens into, an auxiliary suction-chamber 50, which is usually smaller than the gas-supply chamber 20, and which is similarly provided by a dished plate 51 and a suction-chamber diaphragm 52, or other flexibly mounted pressure-plate which separates the interior of the suction-chamber 50 from the external atmosphere. This diaphragm 52 is protected externally by a dished cap or cover-plate 53, which may be provided with a vent 55 for

restrictedly venting the space within the cap 53 to the external atmosphere.

The auxiliary suction-chamber 50 is provided with a suction-connection, in the form of a suction-pipe 57, which extends from the suction-chamber 50 to some part of the mixture-outlet portion 17 of the venturi 15, preferably to the engine-side 58 of the throttle-valve 5, as shown in Fig. 1.

The suction-chamber diaphragm 52 is mounted, at its center, on an intermediate part of a diaphragm-stem 64, the inner end of which is normally (when the engine is not running) spaced from the valve-stem extension 34', as shown at 65 in Fig. 2. The suction-chamber diaphragm 52 is preferably biased outwardly, away from the valve-stem extension 34', by means of a spring 66, which abuts against an adjusting nut 67 which is threaded within the tubular extension 49. This adjusting-nut 67 is provided with a guide-hole 68, for slidably guiding the inwardly extending portion of the diaphragm-stem 64, as shown in Fig. 2. When the suction-chamber diaphragm 52 is drawn inwardly, by a sub-atmospheric pressure in the suction-chamber 50, as will be subsequently described, the inwardly extending portion of the diaphragm-stem 64 will close the space 65 and come into engagement with the valve-stem extension 34', so that the suction-chamber diaphragm-stem 64 thus acts as an idling-assisting mechanical-connection means, between the suction-chamber diaphragm 52 and the carburetor-valve 33, for assisting the main carburetor-opening diaphragm 22 in opening the carburetor-valve 33 during the starting and the idling of the engine (not shown), as will be subsequently described.

Means should be provided for limiting the inward movement of the suction-chamber diaphragm 52. In Fig. 2, the means to this end is a centrally disposed, outwardly projecting, guide-sleeve 69 which is secured to a central hole in the suction-chamber cover-plate 53. The outwardly extending part of the diaphragm-stem 64 extends slidably all the way through this guide-sleeve 69, and is provided, on its end, with an idling-adjustment nut 71, which is backed by a lock-nut 72. In the normal (no-suction) position of the suction-chamber diaphragm-stem 64, there is thus a certain end-spacing 73 between the adjustment-nut 71 and the end of the guide-sleeve 69, which may be adjusted to regulate the amount of suction-chamber valve-opening of the carburetor-valve 33 to a small fixed amount suitable for the idling-operation of the engine (not shown).

In operation, when the engine (not shown), which is connected to the discharge-end 58 of the throttle-valve 5 in Fig. 1, is not running, the carburetor-valve 33 (Fig. 2) is closed tightly, so that no gas can flow therethrough. When the high-pressure gas is first supplied to the regulator-inlet 7, the regulator-diaphragm 11 automatically opens once, very quickly and very slightly, to admit a tiny amount of gas, just enough so that the internal-regulator-pressure reaches the small pressure-differential, over the ambient atmospheric pressure, which is necessary to completely close the regulator-valve 9. Under these static conditions, the closed carburetor-valve 33 (Fig. 2) holds this very slight critical pressure within the regulator 3, and no gas will flow continuously through either the regulator-valve 9 (Fig. 1) or the carburetor-valve 33 (Fig. 2).

When the engine (not shown) is rotated during the starting-operation, the throttle 5 should be left "closed," unless a choke-valve (not shown) is used in the air-in-take 16. Under these conditions, the rotating-engine, previous to its starting, develops a suction at the engine-end 58 of the closed throttle-valve 5, and thus suction is communicated, by the suction-pipe 57, to the suction-chamber 50 (Fig. 2), which draws in the suction-chamber diaphragm 52 to the full amount permitted by the idling-adjustment spacing 73 of the adjusting-nut 71 on the outer end of the diaphragm-stem 64. This provides a small and constant idling-adjustment, or slight opening of the carburetor-valve 33, thus permitting gas to flow, at a constant slow rate, through the carburetor-valve 33, and then through the gas-supply chamber 20, the gas-supply connection 26, the venturi mixture-outlet 17, and the "closed" throttle-valve 5, to the engine (not shown) which is connected at 58 (Fig. 1).

As soon as the carburetor-valve 33 opens, the suctions of both the engine and the venturi 15 are communicated, through the low-pressure gas-pipe 44, to the regulator 3, dropping the internal regulator-pressure below the critical pressure which holds the regulator-valve 9 closed. Thus,

the regulator-valve opens by whatever amount is needed to supply the rate of gas-flow which is called for by the amount of valve-opening of the carburetor-valve 33.

During the idling-operation, the suctions of both the engine and the venturi 15 are communicated, through the gas-supply connection 26, to the gas-supply chamber 20, thus drawing the main carburetor-opening diaphragm 22 inwardly, thus developing a force which tends to open the carburetor-valve 33 against the bias of its closing-spring 38. This action, by itself, however, that is, without the aid of my auxiliary suction-chamber 50, has proved to be not very smooth or constant, so that it is much preferable to make the adjustment such that the main diaphragm 22, during idling, is not quite able, alone, to cause the required idling-opening of the carburetor-valve 33, so that the auxiliary suction-chamber diaphragm 52 controls the idling-opening of the carburetor-valve 33 by holding it fixed at the amount which is set by the idling-adjustment spacing 73.

During the idling-operation also, the auxiliary suction-chamber 50 is restrictedly vented into the external chamber 24 of the main carburetor-diaphragm 22, through the small clearances between the bore 68 and the pin 64, and between the bore 48 and the pin 34'. These clearances are shown exaggerated, in Fig. 2, for clearness of illustration, but they are preferably small enough so that air is slowly sucked therethrough, by the auxiliary suction-chamber, thus somewhat reducing the valve-opening pressure of the main diaphragm 22 during the idling of the engine. This helps to prevent the main diaphragm 22 from opening the carburetor-valve 33 any wider than is provided for by the idling-setting 73 of the suction-chamber diaphragm 52, during idling. At the same time, the external chamber 24 of the main diaphragm 22 is restrictedly vented to the outside atmosphere by the vent 25, which thus tends to bring the pressure in said external chamber 24 up close to the prevailing atmospheric pressure.

When the engine (not shown) is first being started, the initial opening-movement of the carburetor-valve 33 is assisted by the opening-spring 46, which partially counteracts the closing-spring 38 by exerting a valve-opening spring-force which is strongest when the valve 33 is closed, and which quickly becomes smaller when said valve begins to open. This makes it easier for the suction-chamber diaphragm 52, with the aid of the diaphragm 22 on the gas-supply chamber, to open the carburetor-valve 33 and admit some gas to the engine when the engine is being started.

When the engine passes its idling stage, and begins to carry a useful load, with the carburetor valve 33 opened more widely, the pressure of the opening-spring 46 will preferably fall off to nothing, or at least it will be much smaller. This is desirable because, under these running-conditions, the engine exerts a sufficiently strong suction on the carburetor to give the main diaphragm 22 adequate control over the carburetor-valve 33, the effective pressure-area of said main diaphragm 22 being sufficiently large so that the carburetor-valve 33 will begin to open, and remain open, in response to a reasonably small suction in the gas-supply chamber 20. In this way, the engine gets as much gas as it may need, depending upon the amount of opening of the throttle-valve 5. I have found that the joint use of an opening-spring 46, as well as a closing-spring 38, makes it much easier to obtain the proper control over the carburetor-valve 33.

When the engine is running under load, the throttle 5 is always open, so that the engine-suction on the suction-pipe 57 is very much reduced, so much so that the suction-chamber diaphragm 52 is practically put out of commission, and the carburetor-valve 33 is then under the sole control of the main diaphragm 22.

The carburetor-valve 33, like the regulator-valve 9, has a long, tapered, conical shape, so that it has a gas-metering action, admitting progressively increasing rates of gas-flow, depending sensitively upon the amount of opening-movement of the carburetor-valve 33. When the engine is operating under load, these two gas-metering valves 33 and 9 thus operate smoothly together, the carburetor-valve 33 determining the rate of gas-flow into the engine, while the regulator-valve 9 opens by whatever amount is necessary to hold the internal gas-pressure in the regulator 3 at a fairly constant low-pressure value which is somewhere around atmospheric

pressure, varying from a maximum pressure which is preferably only a few ounces per square inch higher than atmospheric pressure, and ranging, at full throttle, to a minimum pressure which is preferably only a few ounces per square inch lower than atmospheric pressure. Thus the gas-delivery pressure, to the carburetor, remains approximately constant, at about the atmospheric pressure, whatever may be the gas-flow requirements. This combination of the two gas-metering valves 9 and 33 thus results in an extremely smooth engine-performance.

The vents or breather-openings 13, 25 and 55, for the spaces on the outer sides of the various diaphragms 11, 22 and 52, also provide a means for adjusting the performances of the associated diaphragms, principally operating as damping-means for preventing pumping or overshooting of the respective diaphragms. Thus, when a sudden pressure-drop occurs on the inner face of any diaphragm, the diaphragm moves inwardly and creates a slight restraining-suction on its outer face, because the vent does not admit air fast enough to maintain atmospheric pressure on the outer face of the diaphragm at the instant when the diaphragm suddenly moves inwardly. A similar damping-effect is exerted by the vent, when its associated diaphragm suddenly moves outwardly. In this way, each diaphragm begins to slow down as it approaches its final position in response to any sudden pressure-change, thus preventing overshooting, and contributing to smooth engine-performance. The vents 13, 25 and 55 are adjustable, so that their damping-actions may be properly predetermined.

The vent 55, which is associated with the auxiliary suction-chamber diaphragm 52, is in parallel with the clearance-space which is provided between the bore of the guide-sleeve 69 and the pin 64, this clearance-space being exaggeratedly shown in Fig. 2, as explained in connection with the bores 68 and 48. Sometimes, this clearance-space within the guide-sleeve 69 may provide all the venting which is necessary for the outer face of the auxiliary idling-controlling diaphragm 52, in which case the associated vent 55 may be omitted.

While I have shown my invention in but a single illustrative form of embodiment, I wish it to be understood that considerable modifications may be made, by way of substitution of equivalents, or by the addition or omission of various parts or refinements, or by changes in the relative positions, sizes or adjustments of the various parts, without departing from the essential spirit of the invention. I desire, therefore, that the appended claims shall be accorded the broadest construction consistent with their language.

I claim as my invention:

1. In a gas-carburetting apparatus for supplying a gas-and-air mixture to an engine, the combination including: a gas-pressure regulator having a high-pressure gas-inlet, a low-pressure gas-outlet in communication with the internal pressure within the regulator, a gas-metering regulator-valve which is movable, from a position closing said high-pressure gas-inlet, to various amounts of valve-openings, for admitting progressively increasing rates of gas-flow depending sensitively upon the amount of opening-movement of the regulator-valve, a flexibly mounted regulator-controlling pressure-plate, separating the interior of the regulator from the external atmosphere, and a regulator-operating mechanical-connection means, between said regulator-controlling pressure-plate and the regulator-valve, for closing the regulator-valve in response to a predetermined critical outlet pressure of the regulator, the effective pressure-area of the regulator-controlling pressure-plate being sufficiently large so that the regulator-valve is closed when the outlet pressure of the regulator is approximately that of the surrounding atmosphere; and a gas-carburetor comprising a venturi having an air-inlet end and a mixture-outlet end, a gas-supply chamber, a gas-supply connection between the gas-supply chamber and a suction-point in the venturi, a gas-inlet chamber connected to the regulator-outlet, a gas-outlet from said gas-inlet chamber to said gas-supply chamber, a gas-metering carburetor-valve which is movable, from a position closing said inlet-chamber outlet, to various amounts of valve-openings, for admitting progressively increasing rates of gas-flow depending sensitively upon the amount of opening-movement of the carburetor-valve, carburetor-valve closing-means for yieldably biasing said carburetor-valve toward its closed position, means for limiting the maximum

opening-movement of the carburetor-valve, a flexibly mounted carburetor-controlling pressure-plate, separating the interior of the gas-supply chamber from the external atmosphere, and a carburetor-operating mechanical-connection means, between said carburetor-controlling pressure-plate and the carburetor-valve, for causing a gas-metering opening of said carburetor-valve in response to a suction within said gas-supply chamber, the effective pressure-area of the carburetor-controlling pressure-plate being sufficiently large so that the carburetor-valve will begin to open in response to a reasonably small suction in the gas-supply chamber.

5 2. The invention as defined in claim 1, characterized by the critical output regulator-pressure, below which the regulator-valve begins to open, being slightly above the external atmospheric pressure, whereby, when the carburetting apparatus is not delivering any gas-and-air mixture to the engine, the closed carburetor-valve enables the regulator to maintain said critical output regulator-pressure therein.

10 3. The invention as defined in claim 1, characterized by the regulator-operating mechanical-connection means including a motion-reducing mechanism resulting in greater forces on the regulator-valve than the forces developed by the regulator-controlling pressure-plate.

20 4. The invention as defined in claim 1, characterized by the regulator-operating mechanical-connection means including a second-class lever.

25 5. The invention as defined in claim 1, in combination with a carburetor-valve opening-spring, mounted so as to exert an opening-force on the carburetor-valve when the carburetor-valve is closed, the valve-opening spring-force becoming smaller when the carburetor-valve begins to open.

30 6. The invention as defined in claim 1, in combination with a carburetor-part for providing an auxiliary suction-chamber, a suction-connection between the mixture-outlet portion of the carburetor and said auxiliary suction-chamber, a flexibly mounted suction-chamber pressure-plate separating the interior of the auxiliary suction-chamber from the external atmosphere, an idling-assisting mechanical-connection means, between said suction-chamber pressure-plate and the carburetor-valve, for causing a small opening of the carburetor-valve in response to a suction within said auxiliary suction-chamber, and idling-controlling means for limiting the valve-opening movement of said idling-assisting mechanical-connection means.

35 7. The invention as defined in claim 6, characterized by a cover-plate over the external side of the carburetor-controlling pressure-plate to form an external chamber therefor, means for restrictedly venting said external chamber to the external atmosphere, and means for restrictedly venting the auxiliary suction-chamber to said external chamber.

40 8. The invention as defined in claim 1, in combination with an engine-throttle valve on the mixture-outlet end of the venturi, a carburetor-part for providing an auxiliary suction-chamber, a suction-connection between the engine-side of said throttle valve and said auxiliary suction-chamber, a flexibly mounted suction-chamber pressure-plate separating the interior of the auxiliary suction-chamber from the external atmosphere, an idling-assisting mechanical-connection means, between said suction-chamber pressure-plate and the carburetor-valve, for causing a small opening of the carburetor-valve in response to a suction within said auxiliary suction-chamber, and idling-controlling means for limiting the valve-opening movement of said idling-assisting mechanical-connection means.

45 9. The invention as defined in claim 8, characterized by a cover-plate over the external side of the carburetor-controlling pressure-plate to form an external chamber therefor, means for restrictedly venting said external chamber to the external atmosphere, and means for restrictedly venting the auxiliary suction-chamber to said external chamber.

50 10. A gas-carburetor comprising a venturi having an air-inlet end and a mixture-outlet end, a gas-supply chamber, a gas-supply connection between the gas-supply chamber and a suction-point in the venturi, a gas-inlet chamber having a gas-inlet, a gas-outlet from said gas-inlet chamber to said gas-supply chamber, a gas-metering carburetor-valve which is movable, from a position closing said inlet-chamber outlet, to various amounts of valve-openings, for admitting progressively increasing rates of gas-flow depending sensitively upon the amount of opening-

movement of the carburetor-valve, carburetor-valve closing-means for yieldably biasing said carburetor-valve toward its closed position, means for limiting the maximum opening-movement of the carburetor-valve, a flexibly mounted carburetor-controlling pressure-plate, separating the interior of the gas-supply chamber from the external atmosphere, a carburetor-operating mechanical-connection means, between said carburetor-controlling pressure-plate and the carburetor-valve, for causing a gas-metering opening of said carburetor-valve in response to a suction within said gas-supply chamber, the effective pressure-area of the carburetor-controlling pressure-plate being sufficiently large so that the carburetor-valve will begin to open in response to a reasonably small suction in the gas-supply chamber, and a carburetor-valve opening-spring mounted so as to exert an opening-force on the carburetor-valve when the carburetor-valve begins to open.

11. A gas-carburetor comprising a venturi having an air-lift end and a mixture-outlet end, a gas-supply chamber, a gas-supply connection between the gas-supply chamber and a suction-point in the venturi, a gas-inlet chamber having a gas-inlet, a gas-outlet from said gas-inlet chamber to said gas-supply chamber, a gas-metering carburetor-valve which is movable, from a position closing said inlet-chamber outlet, to various amounts of valve-openings, for admitting progressively increasing rates of gas-flow depending sensitively upon the amount of opening-movement of the carburetor-valve, carburetor-valve closing-means for yieldably biasing said carburetor-valve toward its closed position, means for limiting the maximum opening-movement of the carburetor-valve, a flexibly mounted carburetor-controlling pressure-plate, separating the interior of the gas-supply chamber from the external atmosphere, a carburetor-operating mechanical-connection means, between said carburetor-controlling pressure-plate and the carburetor-valve, for causing a gas-metering opening of said carburetor-valve in response to a suction within said gas-supply chamber, the effective pressure-area of the carburetor-controlling pressure-plate being sufficiently large so that the carburetor-valve will begin to open in response to a reasonably small suction in the gas-supply chamber, an auxiliary suction-chamber, a suction-connection between the mixture-outlet portion of the carburetor and said auxiliary suction-chamber, a flexibly mounted suction-chamber pressure plate separating the interior of the auxiliary suction-chamber from the external atmosphere, an idling-assisting mechanical-connection means, between said suction-chamber pressure-plate and the carburetor-valve, for causing a small opening of the carburetor-valve in response to a suction within said auxiliary suction-chamber, and idling-controlling means for limiting the valve-opening movement of said idling assisting mechanical-connection means.

12. The invention as defined in claim 11, characterized by a cover-plate over the external side of the carburetor-controlling pressure-plate to form an external chamber therefor, means for restrictedly venting said external chamber to the external atmosphere, and means for restrictedly venting the auxiliary suction-chamber to said external chamber.

13. In a gas-carburetting apparatus for supplying a gas-and-air mixture to an engine, the combination including: a gas-carburetor comprising a venturi having an air-inlet end and a mixture-outlet end, a gas-supply chamber, a gas-supply connection between the gas-supply chamber and a suction-point in the venturi, a gas-inlet chamber having a gas-inlet, a gas-outlet from said gas-inlet chamber to said gas-supply chamber, a gas-metering carburetor-valve which is movable, from a position closing said inlet-chamber outlet, to various amounts of valve-openings, for admitting progressively increasing rates of gas-flow depending sensitively upon the amount of opening-movement of the carburetor-valve, carburetor-valve closing-means for yieldably biasing said carburetor-valve toward its closed position, means for limiting the maximum opening-movement of the carburetor-valve, a flexibly mounted carburetor-controlling pressure-plate, separating the interior of the gas-supply chamber from the external atmosphere, a carburetor-operating mechanical-connection means, between said carburetor-controlling pressure-plate and the carburetor-valve, for causing a gas-metering opening of said carburetor-valve in response to a suction within said gas-supply chamber, the effective pressure-area of the carburetor-controlling pressure-plate being sufficiently large so that the carburetor-valve will begin to open in response to a reasonably small suction in the gas-supply chamber, an engine-throttle valve on the mixture-outlet end of the venturi, a carburetor-part for providing an auxiliary suction-chamber, a suction-connection between the engine-side of said throttle valve and said auxiliary suction-chamber, a flexibly mounted suction-chamber pressure-plate separating the interior of the auxiliary suction-chamber from the external atmosphere, an idling-assisting mechanical-connection means, between said suction-chamber pressure-plate and the carburetor-valve, for causing a small opening of the carburetor-valve in response to a suction within said auxiliary suction-chamber, and idling-controlling means for limiting the valve-opening movement of said idling-assisting mechanical-connection means.

14. The invention as defined in claim 13, characterized by a cover-plate over the external side of the carburetor-controlling pressure-plate to form an external chamber therefor, means for restrictedly venting said external chamber to the external atmosphere, and means for restrictedly venting the auxiliary suction-chamber to said external chamber.
